United States Patent Office

Des. 197,933
Patented Apr. 7, 1964

197,933

AIRPLANE

Arthur H. Sumner, 150 W. Bayberry Road, Islip, N.Y.

Filed Jan. 28, 1963, Ser. No. 73,354

Term of patent 3½ years

(Cl. D71—1)

FIG. 1

FIG. 2

FIG. 3

FIG. 4

FIG. 5

FIG. 1 is a perspective view of an airplane showing my new design;

FIG. 2 is a top view of the plane;

FIG. 3 is a perspective view taken from one side of the tail of the plane;

FIG. 4 is a front view, and

FIG. 5 is a rear view of the plane.

This application is a continuation-in-part of application Serial No. D. 62,244 filed Sept. 23, 1960 and now abandoned.

I claim:

The ornamental design for a airplane, as shown and described.
